PUNCH PRESS MECHANISM

William R. Beatty, Hammond, Ind.

Application March 23, 1931. Serial No. 524,535

14 Claims. (Cl. 164—87)

This invention relates to metal working machinery, and more particularly to mechanism for moving and positioning the material to be operated upon.

5 One of the objects of the invention is the provision of new and improved mechanism for conducting the material to be operated upon to and from the metal working machinery, together with novel means for transferring and positioning the material to be operated upon.

10 Another object of the invention is the provision of a new and improved punch press having novel arrangement of the parts whereby the operator may inspect the operation of the press on the material from a point in front of the press.

15 A further object of the invention is the provision of a new and improved punch press having novel means for operating the tools.

20 A still further object of the invention is the provision of a material transferring member or unit for transferring material from one punch press table to another.

25 Another object of the invention is the provision of a new and improved punch press having novel spacing and supporting tables together with new and improved means for rotating the work and transferring the same from one table to the other, that is inexpensive to manufacture, comparatively simple in construction, composed of few moving parts, and that is effective in operation.

30 Other and further objects and advantages will appear from the following description taken in connection with the accompanying drawings, in which

Fig. 1 is a front elevation of the device shown more or less diagrammatically;

Fig. 2 is a plan view thereof;

Fig. 3 is a section on line 3—3 of Fig. 2;

40 Fig. 4 is a transverse, vertical section through a portion of the punch press;

Fig. 5 is a rear elevation of the press, with parts broken away;

Fig. 6 is a section on line 6—6 of Fig. 4;

Fig. 7 is a section on line 7—7 of Fig. 1;

Fig. 8 is a section on line 8—8 of Fig. 1; and

Fig. 9 is a section on line 9—9 of Fig. 3.

45 It is common practice in punch press mechanism, especially in the heavy presses where the largest forms of commercial channel bars, angle irons, I-beams and the like are operated upon, to employ a press with a closed throat. Because of the tremendous pressures developed it has heretofore been regarded as necessary to employ this type of press in order to resist this pressure.

Such an arrangement necessitates the operator viewing the work from the side instead of from the front of the press.

50 Where it is desired to punch both the webs and the flanges of the bars or beams it has been the common practice to punch either the web or the flanges in one passage of the work through the press and then by proper hoists remove the bar from the spacing table and turn it to the position to punch the flanges. This is a slow and 60 laborious process and is attended with considerable difficulty in properly positioning the bar on the table.

55 The present invention seeks to eliminate these difficulties by the provision of a new and improved press having an open throat whereby the operator can view the work from the front of the press during the operation of the same, and by the provision of a novel mechanism for turning the bar through 90° after the flanges, for 65 example, have been punched, and properly positioning it on the table for punching the web, or vice versa.

60 In the form of construction selected to illustrate one embodiment of the invention, the reference character 10 designates a punch press, 11 designates generally the spacing table, and 12 the supporting table which extends alongside the spacing table 11. The means for supporting the 70 work shown at the left of the punch in Fig. 1, and the means for supporting the work alongside the spacing table at both sides of the punch, see Fig. 2, are each composed of a plurality of independent supporting stands or supporting members, but for convenience of description the former will be considered as a portion of the spacing table and the latter taken collectively will be 75 termed the supporting table. The transfer or bar turner members are shown at 13. The punch 80 press comprises a frame 14 which rests on a concrete base 15 and carries a bed plate 16 and a head 17 supported by an arm 18 overhanging the bed plate. For convenience of description the arm 18 will be considered as extending upwardly and forwardly from the base of the press 85 in the rear thereof.

85 Slidably mounted in the head 17, see Fig. 4, is a ram 19 having the ram bolster plate 21 secured in the usual manner to its lower face. Suitable tool supports 22 are attached to the plate 21 and each is provided with slideable gag plates 23 and 24, see Fig. 6, which are adapted to be moved into position above the tools 25 and 26 respectively. These plates are moved by levers 27. 90

Since they are all substantially alike, only one need be described.

The lever 27 is connected to a shaft 28 to which is rigidly connected an arm 29 which in turn is connected to the corresponding block 23 as by means of the link 31. The tools 25 and 26 are slidably mounted in the support 22 and when it is desired that they should be employed to punch the material beneath the same, the corresponding block is slid inwardly above the tool to prevent it from sliding upwardly in the holder when the ram is forced downwardly by the toggle mechanism that will presently be described.

Suitable stripper members 32 and 33 are attached to the head and extend downwardly adjacent to the lower ends of the tools 25 for stripping the work from the tools after the punching operation. Since the details of this portion of the punch press mechanism constitute no part of the present invention it is not thought necessary to further illustrate or describe the same.

The device is so constructed that punching tools 22 may be arranged for a single bar on one of the tables, or they may be so arranged that a bar on each table may be punched simultaneously, as indicated in Fig. 4 of the drawing. The press illustrated is designed for any type of work, but is especially constructed for the punching of the heaviest commercial bars and beams, and in order that the pressure shall be equalized on the ram, suitable means are provided for insuring uniform movement of all parts of the ram face during the operation of the machine.

Any suitable mechanism may be employed for that purpose. In the form of construction shown, toggle mechanism is employed for this purpose.

Referring now to Fig. 4, a pair of links 34 and 35 pivotally connected together and having the upper end pivotally mounted on a shaft 36 carried by the head 17 and having its lower end pivotally connected to a shaft 37 carried by the ram 19 at the front thereof, and a similar pair of toggle links 38 and 39 pivotally connected as at 41 at the rear of the head 17, are employed. The toggle members are pivotally connected at their inner ends to the operating bar 42 which is adapted to be operated by a link 43 pivotally connected at its forward end to the bar 42 and connected to an eccentric 44 at its rear end.

50 The eccentric 44 is rotated by a shaft 45 which in turn is operated by the motor 46 through a chain of reducing gears 47, 48, 49 and 51, see Figs. 4 and 5 of the drawings.

The toggle is so arranged that it is operated to 55 depress the ram when it is pulled toward what for convenience of description will be termed the rear of the machine. By means of this arrangement the force for operating the toggles will react on the head in an upward and a rearward 60 direction whereby that portion of the head in front of the ram may be made quite thin so that it will present a minimum obstruction to the operator in watching the work from the front of the press during its operation. The front of the head may if desired be provided with an opening 65 having a closure 53 therefor.

The ram is preferably provided with recesses 54 and 55 at its upper end for receiving the upper pivot pins for the toggle members as clearly 70 shown in Fig. 4 of the drawings. A counterweight is preferably though not necessarily provided for the ram. As shown, a counterweight 56 slidably mounted on an arm 57 which in turn is pivoted to a support 58 is employed for this purpose. The 75 forward end of the arm 57 is connected to the

ram 19 by means of a link 59 and a threaded bolt 64 pivoted to said link at its upper end and detachably connected to a connecting bar 62 extending across the upper portion of the ram.

Suitable means are provided for assisting in elevating the ram. As shown, a compression spring 63 mounted on the upper end of the bolt 64 which extends through a cross member 62 on the ram 19 and through a stirrup 66 supported from the upper portion of the head is employed for this purpose. By means of this arrangement the ram will be retained in its elevated position when the device is not operating, and may move vertically relative to the weight 56 due to the tension of the spring 63.

The press is provided with the usual punching tool bolster 67 on which are mounted the die members 68 for the punching tools. If desired, the shaft 52 on which the gears 48 and 49 are mounted may be provided with a fly wheel 69 and the shaft 45 on which the eccentric 44 is mounted may be provided with a connecting rod counterbalance 71, see Fig. 5.

Suitable clutch mechanism is provided for the press whereby the same may be disconnected from the motor or connected thereto when desired. In the construction shown, the parts are so arranged that the clutch cannot be disconnected except when the ram 19 is at its upper limit of movement. Mechanism for accomplishing this will 105 now be described.

Referring now to Figs. 4 and 5 the clutch is shown at 72 and comprises the jaw 73 rigidly connected with the gear 47 and rotatably mounted on the shaft 45, and the shiftable jaw member 74 110 slidably mounted on but keyed to said shaft. The jaw member 74 is shifted into and out of gear by a yoke 75 which in turn is operated by a bell crank arm 76 fixed relative to said yoke. The arm 76 is operated by a treadle 77 through a link 78, a bell crank arm 79, a link 81, a lever 82, and an extensible link 83 which is connected to the outer end of the lever 82 and the arm 76.

In order that the machine may be controlled from a number of positions, a plurality of treadles 120 77 are provided for operating the rod 78. The link 83 is formed in sections and the sections are telescopically connected, the same being provided with a spring 84 for yieldingly resisting the extension of the link.

The means for preventing the disengagement of the clutch except when in a predetermined position, that is, when the ram is at its upper limit of travel, comprises a cam 85 which is adapted to be 130 engaged by a slidable finger 86 when the same is moved into the path of said cam. The finger is moved when the treadle 77 is operated. This is accomplished by a link 87 connected at its upper end to said finger and at its lower end to a crank arm 88 rigidly connected to the shaft 39 on which 135 the bell crank arm 79 is mounted. A spring 91 having one end connected to the frame of the punch and its other end connected to the bell crank 79 is adapted to normally hold the bell crank 79 in its upper position for declutching the 140 mechanism.

In the operation of this feature of the device, when it is desired to declutch the mechanism, the pedal or treadle 77 is released, which will move the extensible link 83 downwardly against the 145 compression of the spring 84, but because of the friction of the cooperating teeth on the clutch jaws this movement alone will not declutch the mechanism. Simultaneously with the downward movement of the link 83 the link 87 will be forced 150

upwardly, carrying with it the finger 86 which will be moved into the path of the cam member 85 and when the jaw 74 rotates to bring the cam into engagement with the finger 86 the cam will force the jaw to the left in Fig. 5, thereby de-clutching the mechanism, when the ram is in elevated position.

In the clutching operation, the treadle 77 is depressed, and this in turn will move the yoke 75 to the right in Fig. 5 and simultaneously withdrawing the finger 86, thereby directly causing the interengagement of the teeth on the jaws 73 and 74.

The spacing table comprises the usual frame members 91 which are mounted on stands or supports 92 spaced along the table. Suitable work supporting rollers 93 are provided as is usual in such constructions.

Mounted on the frame 91 is a carriage designated generally by the reference character 94. This carriage may be of the usual or any well known construction and is provided with grip jaws 95 for engaging the end of a bar, beam or other work that is being operated upon. The carriage is moved backwardly and forwardly along the table by a hand wheel 96 having the gear 97 thereon, which is adapted to engage a rack 98 on the table. Since the details of this portion of the carriage constitute no part of the present invention, it is not thought necessary to further illustrate or describe the same.

As shown on the drawings, a single carriage is employed. The spacing table 11 may be considered as extending to each side of the press and on the side opposite the press from the carriage the table may comprise the supports or standards 99, each having the supporting rollers 101 at their upper ends.

In the punching of large commercial bars, as for instance I-beams, the same are placed on the spacing table with the webs of the bars resting on the roller supports and the bar is moved along the table by the carriage 94 through the punching press in the usual manner.

Suitable means are provided for turning the bar through 90° so that after the webs have been punched the flanges may also be punched. Any suitable mechanism may be employed for this purpose. In the form of construction selected to illustrate one embodiment of the invention the mechanism shown in Fig. 8 is employed for this purpose.

A plurality of transfer or bar turning members 13 are employed, located at suitable distances along the spacing table. Since these devices are all the same in construction, only one need be described. As shown, this member comprises a pair of supports 102 and 103 between which at their upper ends is pivotally supported a geared quadrant 104. A pair of cylinders 105 and 106 are mounted on or rigidly connected to the quadrant 104. Pistons 107 and 108 are mounted in these cylinders and rigidly attached to their upper ends is the bar support 109, see Fig. 8. The quadrant 104 is operated by a pinion 104' on the shaft 120 which extends beneath all the bar turning members 13 for operating them simultaneously. The shaft is operated by suitable means as the motor 130 through a worm drive 140, see Fig. 2.

Slidably mounted on this support is a gauge or guide 110 as more clearly shown in Figs. 8 and 9 of the drawings. This guide is held in adjusted position by the spring-pressed pin 111 which is adapted to engage suitable recesses 112

formed along the upper surface of the support 109. The pistons 107 and 108 are adapted to be forced upwardly by steam or compressed air which is introduced through suitable conduits 113 at the bottom of the cylinders.

The supporting table is mounted alongside the spacing table and comprises a plurality of hollow supporting stands designated generally by the reference character 114, see Fig. 7, in each of which is telescopically mounted a standard 115 carrying a yoke 116 in which is mounted a supporting roller 117. The inner arm of the yoke 116 is preferably extended and an anti-friction roller 118 is mounted thereon for engaging the flange of the bar 119 for guiding the same along the table as clearly shown in Fig. 7 of the drawings.

The standards 115 are adapted to be adjusted vertically simultaneously by a shaft 121 which extends along the supporting table. This shaft has suitable gears 122 which are adapted to engage rack teeth 123 on the standards 115. The shaft 121 is adapted to be operated in any suitable manner as by means of a motor 124 through a worm drive 125 or in any other suitable manner.

The carriage 94 is provided with means for conducting the work along the supporting table. In the form of construction shown, see Fig. 2, the carriage is provided with an outwardly extending arm 126 to which is rigidly connected a head 127 having a vertical opening therethrough in which is slidably mounted an arm 128, see Fig. 3.

The arm 128 is adapted to be raised and lowered by a hand wheel 129 which is adapted to operate a rack and pinion associated with said head and arm. The lower end of the arm is adapted to have attached thereto a link 131, the forward end of which is bifurcated as shown at 132 in Figs. 2 and 3, the bifurcations being provided with set screws 133 and 134 for attaching the same to the web of a bar or beam that is being operated upon. The forward end of the link 131 is adapted to be raised and lowered so that the same may be attached to the central line of the beam to insure accuracy in positioning the holes in case it becomes necessary to turn the beam for punching the top flanges after the bottom flanges have been punched, or vice versa.

In the operation of the device, assuming that the I-beam is supported on the auxiliary table 125 on the rollers 117, see Figs. 2 and 7, and it is desired to move the same on to the spacing table and turn the beam through an angle of 90° so that the web will rest on the rollers 101, as indicated in dotted lines in Fig. 7, the bar turning member is operated to turn the bar support 109 to a vertical position as shown in Fig. 2, after which the pistons 107 are forced outwardly to bring the guide or gauge 110 beneath the bar, after which the quadrant 104 is turned to the position shown in Fig. 8 and the pistons are lowered for depositing the bar on the rollers 101. The operation is reversed when it is desired to change the beam from the rollers 101 to the rollers 117.

I claim as my invention:

1. In a device of the class described, a table having two sets of rollers associated therewith, a traveling carriage on said table, jaws carried by said carriage and adapted to engage a flanged beam, means for operating said carriage for moving said beam along one set of said rollers, and means for rotating said beam through ninety degrees and depositing the same on the other set of rollers.

2. In combination, a punch having a base, a head overhanging said base for forming an open throat, a pair of tool-holding members carried by said head, a table having two sets of conveyor rollers extending longitudinally thereof, a carriage movable along said table and having means for engaging a flanged beam for moving the same along either set of said rollers beneath the corresponding tool holding member, and means for elevating said beam from one set of said rollers, giving the same a partial rotation and depositing the same on the other set of rollers. 80
3. In metal working mechanism, a press, punching tools carried by said press, a spacing table, a supporting table alongside of said spacing table, a carriage for conducting material along said tables to and from said press, means for transferring said material from one table to the other and means for operating said punching tools for perforating said material, said press having an open throat whereby the operator may see the operation of the tools from either the side or front of said press. 90
4. In combination, a punch press having a vertically moving head, a toggle at each end of said head for operating the same, a pair of tables for supporting material to be worked upon, means for elevating one of said tables to the exclusion of the other, means for moving said material toward said press to be operated upon and for removing the material from said press, said press having an open throat whereby the punching operations will be visible to said operator from a position in front of said press. 100
5. In combination, a punch press, a spacing table having rollers thereon for supporting a metallic bar on its side, a supporting table having rollers thereon for supporting said bar in upright position, and means for elevating one of said tables and for transferring said bar laterally from one table to the other. 110
6. In metal working mechanism, a punch press comprising a frame, a bed plate, an arm extending upwardly and outwardly from said plate, a head supported by said arm above said plate said arm being supported solely from its base at the rear for forming an unobstructed open throat for said press, a ram slidably mounted in said head, a set of toggle links at the rear and a set at the front of said ram, a drawbar secured to said links, and means for pulling said bar rearwardly for straightening said links for lowering said ram and tools carried by said ram. 120
7. In metal working mechanism a punch press, a frame, a bed plate, a head supported by said frame above said bed plate and in spaced relation thereto and forming therewith an open throat, a ram slidably mounted in the forward end of said head, means engaging said head at a plurality of points along the same for raising and lowering the ram, and means for supporting a pair of flanged beams between said head and bed plate, one of said beams being rotated 90 degrees from the other, and tools carried by said head for simultaneously punching holes in the web of one beam and the flanges of the other. 130
8. In metal working mechanism, a beam turning device comprising a stand, a quadrant pivoted to said stand, a pinion geared to said quadrant, a beam support movable with said quadrant, means for raising and lowering said support, and means including said quadrant and pinion for rotating said support through at least 90 degrees. 140
9. In a metal working device, beam turning mechanism comprising a plurality of stands, beam supports movably mounted on said stands, and means for raising and lowering said supports and for turning the same on said stands. 150
10. In metal working mechanism, a spacing table for supporting beams, supporting means alongside said table for supporting beams, and beam turning mechanism for transferring a beam from said table to said supporting means and vice versa, said mechanism comprising beam supporting means and means for raising, lowering and for turning said supporting means. 160
11. In metal working mechanism, spacing and supporting tables for supporting metal beams, means for moving said beams longitudinally along said tables, and power operated means for rotating said beams and for transferring said beams from one of said tables to the other. 170
12. In metal working mechanism, a punch, spacing and supporting tables for said punch, said tables extending to opposite sides of said punch, means for simultaneously moving beams along said tables through said punch, means for raising and lowering said supporting table, and means for transferring beams from one table to the other including means for turning said beam. 180
13. In metal working mechanism, a spacing table for supporting metal members to be operated upon, a carriage on said table for moving said members along said table, a supporting table alongside said spacing table, an outrigger arm on said carriage, and vertically adjustable means carried by said arm and movable with said carriage for engaging a beam for moving the same along said supporting table. 190
14. In a punch press mechanism, a base member, an arm extending upwardly and forwardly from said base member and having a head overhanging said bed plate for forming an open throat, a ram slidably mounted in said head, toggle members flexing forwardly and engaging a plurality of points along said head from front to rear, eccentric mechanism, a pull rod connected to said members and adapted to be moved rearwardly for straightening said toggle members for lowering said ram, tools carried by said head, and means for turning and moving beams beneath said tools for punching said beams in each of their positions. 200

W. R. BEATTY.
